CLAIM

The ornamental design for aero dynamic structure with
fastener arrangement as shown and described.

DESCRIPTION

FIG. 1 is a front perspective view of aero dynamic structure
with fastener arrangement;

FIG. 2 is a front elevation view of the aero dynamic structure
with fastener arrangement;

FIG. 3 is a rear elevation view;

FIG. 4 is a right side view of the aero dynamic structure with
fastener arrangement;

FIG. 5 is a left side view of the aero dynamic structure with
fastener arrangement; and

FIG. 6 is a top view of the aero dynamic structure with
fastener arrangement; and,

FIG. 7 is a bottom view of the aero dynamic structure with
fastener arrangement.

The broken lines illustrate portions of the aero dynamic
structure with fastener arrangement that form no part of the
claimed design. The broken away symbols in the drawings
indicate the appearance of any portion of the article between
the break lines forms no part of the claimed design.
